LAMP SHADE

Kenneth Yuhung Tongson, San Po Kong, Kowloon, Hong Kong, assignor to Star Industrial Company, Limited, San Po Kong, Kowloon, Hong Kong

Filed July 8, 1974, Ser. No. 486,459

Claims priority, application Great Britain May 30, 1974

Term of patent 7 years

Int. Cl. D26—05

U.S. Cl. D48—16 D

FIG. 1

FIG. 2

FIG.3

FIG. 4

FIG. 1 is a front perspective view of the lamp shade showing my new design;

FIG. 2 is a longitudinal cross-sectional view taken on the line 2—2 in FIG. 3;

FIG. 3 is an underneath plan view of the lamp shade of FIG. 1; and

FIG. 4 is a transverse cross-sectional view of the lamp shade taken on the line 4—4 in FIG. 2.

I claim:

The ornamental design for a lamp shade, as shown and described.
